UNITED STATES PATENT OFFICE.

DAVID COHEN, OF NEW YORK, N. Y.

DESIGN FOR A DIRECTION-SIGNAL FOR VEHICLES.

49,642.

Specification for Design.

Patented Sept. 12, 1916.

Application filed April 21, 1916. Serial No. 92,791. Term of patent 3½ years.

To all whom it may concern:

Be it known that I, DAVID COHEN, residing at New York, county and State of New York, have invented a certain new, original, and ornamental Design for a Direction-Signal for Vehicles, of which the following is a specification, reference being had to the accompanying drawing, forming part thereof.

In the drawings Figure 1 is a front elevational view illustrating the design for a direction signal for vehicles; and Fig. 2 is a side elevational view.

The new design comprises a member shaped to represent an eagle with wide spread wings.

Copies of this patent may be obtained for five cents each, by addressing the "Commissioner of Patents, Washington, D. C."

The new design includes further three grand divisions of the casing, viz: a central division comprising the body of the eagle, and two side divisions comprising the two wings of the eagle, the central division having the representation of a shield thereon bearing a warning legend, as for instance, the words "Safety first".

I claim:

The ornamental design for a direction signal for vehicles, as shown and described.

DAVID COHEN.
